[57] **CLAIM**

The ornamental design for a thread dispenser/pleater platform, substantially as shown and described.

DESCRIPTION

FIG. 1 is a top plan view of a thread dispenser/pleater platform, showing my new design.

FIG. 2 is a front elevational view thereof, the rear elevational being substantially similar thereto.

FIG. 3 is a bottom plan view thereof.

FIG. 4 is a right side elevational view thereof, the left side elevation being substantially similar thereto.

FIG. 5 is a cross-section thereof taken on line V—V of FIG. 2, with a pleater and spools of thread shown in broken lines for illustrative purposes only.

FIG. 6 is an exploded perspective view thereof.

FIG. 1

FIG. 2

FIG. 3

FIG. 4
